UNITED STATES PATENT OFFICE.

JAMES A. SHEPARD, OF LEXINGTON, ASSIGNOR TO HIMSELF AND EDWARD A. G. ROULSTONE, OF BOSTON, MASSACHUSETTS

CHEMICAL FIRE-EXTINGUISHER.

SPECIFICATION forming part of Letters Patent No. 224,109, dated February 3, 1880.

Application filed September 18, 1879.

To all whom it may concern:

Be it known that I, JAMES A. SHEPARD, of Lexington, county of Middlesex, and State of Massachusetts, have invented certain Improvements in Chemical Fire-Extinguishers, of which the following is a specification.

This invention relates to a class of fire-engines in which water charged with a mixture of bicarbonate of soda and sulphuric acid within 10 a closed generator is thrown by the pressure within the latter through a hose upon the fire; and it consists in the general construction, as well as mechanical details, of the apparatus, as will be hereinafter described.

The drawings accompanying this specification represent, in Figure 1, a vertical section of a generator embodying my improvements. Fig. 2 is a vertical cross-section of the can containing the chemical liquid. Fig. 3 is a section 20 of the mechanism for opening and closing the pressure-chamber in recharging. Fig. 4 is an elevation of an engine embodying my improvements, while Fig. 5 is a section of the pressure-gage used in common by the two generators and the connections between them.

Heretofore in engines of this class the cylinders or generators in which the chemical solution has been contained have been arranged upright upon their carriage, with the filling-ori- 30 fice at the upper end, and each provided with its own pressure-gage, exhaust-pipe, and other necessary connections.

A notable distinction between this engine and others of its class consists in arranging the two cylinders or generators in a horizontal plane and abutting their inner ends together, (or, what would be the same, providing one cylinder with a central division,) by which means I am enabled to bring the weight of such cylinders and their contents much nearer the axle 40 of the carriage and greatly diminish the general bulk of the engine, in addition to which I employ but one pressure-gage, one exhaust-pipe, and one hose-connection, which are used in common by the two generators.

Referring to the drawings before named, it will be seen that A A' represent two closed cylinders, arranged and confined in a horizontal plane, with their inner ends or heads abutting 50 closely together, and supported within an open

frame, B, which, in turn, is mounted by axles C upon suitable wheels D.

E represents a horizontal pipe, which is disposed alongside the generators A A', and constitutes a hose-connection or delivery-pipe common to the latter, while F F' represent pipes connecting, respectively, with the interior of the generators and the delivery-pipe E, and each provided with a cock, a or a', between the said pipe E and the generators.

The pressure-gage of the engine is shown at G as mounted upon the top of, and connecting with the interior of, an upright hollow standard, H, erected centrally upon the top of the conjoint generator A A', while the said standard consists of two side legs, b b', each of which, at its lower end, connects with the upper part of the interior of one of the said generators, while at its upper end each leg connects with and forms part of a horizontal chamber or passage, c, which constitutes the upper part of the main body of standard H, such body being completed by a second horizontal passage or chamber, d, connecting interiorly with the legs and the passage c.

A cock, e, is placed in the upper end of the standard H, immediately below the pressure-gage, while within the chamber d, and upon each side of its center, are placed two cocks, f f'.

The exhaust-pipe common to the two cylinders is shown at I as connecting at one end with the interior of the chamber d, between the cocks f f', and with its opposite end carried below the cylinders and opening into the 85 atmosphere.

The upper portion or chamber, c, of the standard H is divided by an oblique or zigzag partition, g, which separates the legs b b', and has a central valve-port, h, the arrangement 90 of the shelf being such that one leg is open directly to communication with the pressure-gage, and the other communicating with such gage through the valve-port from below, while the valve, which is shown at i, and is an automatically-operating one, operates with the said valve-port and with a seat, j, formed about the mouth of the leg, which connects directly with the gage, or at the point of intersection 95 of the said leg with the passage c, the valve 100

being hinged at its lower end between the two valve seats or ports, and so as to operate to open or close one or the other, as the case may be. As represented in the accompanying drawings, the leg *b* connects directly with the gage *G*, and the leg *b'* indirectly through the valve-port *h*.

In operating with the engine prior to service at fires the cocks *e f f'* are closed. The jar *H²* having been inverted, and the pressure obtained within one of the cylinders, as stated, (say the cylinder *A*, as the front one is generally first used,) the cock *f* is opened and the water within the cylinder charged with gas is ejected under pressure, through the connecting-pipe *F* and the hose-connection pipe *E*, and thence through the hose upon the fire, the same pressure also extending up the leg *b* and into the pressure-gage, and automatically closing the valve *i* upon the seat or port *h*, and thereby shutting off entrance to the leg *b'* and the opposite generator *A'*, while the closed cock *f'* shuts off entrance at this time to the exhaust-pipe *I*.

Should the contents of the second cylinder, *A'*, be required, its jar is to be inverted and the cock *a'* opened, the water under pressure being thereby allowed to escape through such cock into the hose-connection pipe *E*, while the same pressure closes the valve *i* upon the seat *j*, and passes through the port *h* to the pressure-gage.

When the second tank is emptied, or nearly so, of water, the cock *a'* is closed, and the cock *f'* is opened, which permits the gas in the said generator to escape by the exhaust *I*.

Each generator has at top a filling-opening orifice, *B²*, for permitting introduction into the cylinder of the substance employed to produce the gas required, such opening being provided with a suitable cover or valve, *C²*, secured to or formed with the lower end of a vertical stem or rod, *D²*, which in turn is guided by a tubular head, *A³*, making part of an arched standard, *E²*, disposed upon the top of the generator *A²* and straddling the said cover *C²*.

The cover *C²* is depressed powerfully upon and about the opening by an eccentric hand-lever, *F²*, pivoted to the top of the standard *E²*, and raised from off its seat, when the pressure of the lever is removed by a coiled spring, *G²*, which encircles the stem *D²* and exerts its stress between a collar, *a²*, upon such stem and a shoulder, *b²*, in the upper part of the tubular standard.

The hand-lever *F²* carries a latch, *c²*, which engages with a catch or hook fixed to the adjacent part of the standard *E²*, thereby confining the cover *C²* in its closed position about the opening or filling orifice *B²*.

One leg of the standard *E²*—for instance, *e²*—is pivoted to the top of the generator *A²* in such manner that the entire standard, with the cover *C²* and its hand-lever, may be swung to one side and leave the filling-orifice *B²* unobstructed, in order that access may be readily

had to the latter when it becomes desirable to charge the generator.

The opposite leg, *f²*, of the standard is detachably fastened to a post, *g²*, erected upon the top of the generator, a suitable latch being combined with the two for locking them together and securing the cover *C²* and its adjuncts in proper position over the filling-orifice.

The jar or bottle before alluded to as disposed within the generator *A²* is shown at *H²* as suspended within the upper part of said generator and immediately below the filling-orifice of the latter, the means herein shown of supporting such jar being slotted hangers *h² h²*, depending from the top of the interior of the generator, and trunnions *i² i²*, projecting from opposite sides of the jar and entering such slots, the trunnions finding seats at the bottoms of the slots, and constituting means of enabling the jar to be turned bottom up in order to discharge its contents into the tank below, while the slots in said hangers, which extend upward as far as the filling-orifice *B²*, permit the jar to be lifted out of the generator through such orifice to enable said jar to be readily filled, the jar having at bottom a suitable handle, by which it is to be lifted.

The stopper of the jar is self-acting, and consists of a conical or tapering valve, *j²*, which closes the mouth of the jar, such valve having a stem, *k²*, which extends into the jar and guides the movements of the valve and prevents loss of the latter, the head *l²* of such stem being of greater diameter than the mouth of the jar.

The jar *H²* is estopped from turning in one direction by a stop suitably applied to the hangers *h² h²*, and the opposite side of such jar is weighted to such an extent that when left free to turn upon its trunnions it shall be turned bottom up and remain in this position until reversed.

A suitable catch or hook, *m²*, is affixed to a horizontal rod or rock-shaft, *n²*, which is supported within the upper part of the generator and to one side of the hangers *h² h²*, the said catch or hook operating with a corresponding hook, *o²*, secured to the jar, the arrangement of the whole being such that the jar is confined in an upright position by the catch *m²*, and its contents isolated from those of the generator.

One end of the shaft *n²* extends through the wall of the generator, and is provided with a hand-latch, *p²*, which operates with a catch upon the exterior of such generator to lock such shaft to the generator, and prevents release of the jar *H²*.

The operation of the above-described apparatus is as follows, it being supposed that the generator has received its charge of bicarbonate of soda or other substance, and the jar *H²* its charge of sulphuric acid, or whatever material may be employed, the cover of the generator being tightly closed, and the jar

H^2 being locked in an upright position, and its mouth sealed by its valve, which closes by its own weight:

In the event of a fire the generator is taken to the proper locality, and the attendant seizes and releases the hand-latch p^2 and turns the rock-shaft n^2 sufficiently to disengage the jar H^2 and permit it to turn bottom upward, the valve opening by its own weight and permitting the contents of the jar to be precipitated into those of the generator, the result being the generation of the desired gas, which is taken from the generator through a suitable pipe, as before explained.

15 When the gas within the generator has spent itself or passed off by the exhaust, the pressure of the hand-lever upon the cover of the generator is relaxed and the arched standard disengaged and turned to one side, thereby uncovering the man-hole or filling-orifice of the generator, and permitting the jar H^2 to be lifted up, reversed in position, and refilled, and if necessary, a fresh charge placed in the generator, when the hand-latch p^2 is to be restored to its original position, and the jar thereby securely held upright to the hangers which support it. The engine is now ready to be again brought into use by reversing the jar as at first, and this generation of gas may thus be 25 continued as long as the supply of chemicals holds out.

One merit of my engine will be found to consist in the ease and rapidity with which it may be recharged, as the act of releasing 35 the pressure upon the cover of the man-hole of the generator, and the removal of such cover, to leave the man-hole unobstructed, is accomplished rapidly and with little effort, while the manner of suspending and reversing 40 the jar H , and of automatically opening and closing its mouth, enables the charging of such jar and the discharging of its contents to be carried on with little labor or loss of time.

I claim—

45 1. A chemical fire-extinguisher in which the two cylinders or generators are arranged in a horizontal plane and with their inner ends abutting together.

50 2. In chemical fire-engines in which two pressure-generators are employed, the combination, with such generators, of a single pressure-gage and suitable connections between the two, whereby such gage is operated automatically by pressure from said generator.

3. The hollow standard as composed of the 55 legs b b' , the chambers c and d , and partition g , with the valve i , ports h and j , and the cocks f f' .

4. The combination, with the two generators, arranged as described, of the connecting-pipes 60 F and F' and a swivel hose-connection, substantially as and for the purposes stated.

5. In general combination, the two cylinders 65 A A' , standard H , gage G , and pipes F , F' , and E , substantially as described.

6. In combination with stem or rod D^2 , the arched standard E^2 , pivoted on one side to the top of the generator, and lever F^2 , pivoted on 70 said standard, whereby said rod and cover C^2 are forced downward.

7. In combination with stem or rod D^2 , the spring G^2 , arched standard E^2 , lever F , and cover C^2 , substantially as set forth.

8. In combination with a generating-chamber and suspended receptacle, a slotted guide-frame, within which said receptacle can be 75 raised and lowered.

9. In combination with a generating-chamber and suspended receptacle, a slotted guide-frame within which said receptacle can be 80 raised and lowered, said frame being provided with a device for preventing said receptacle from tipping in one direction, while allowing it to tip in the other.

10. The jar, with its trunnions, and the slotted or grooved hangers, in combination with the filling-orifice of the generator, whereby the jar may be reversed in position to discharge its 85 contents, and lifted up to or through the man-hole, to be returned to an upright position and 90 recharged, substantially as herein described.

11. The combination, with the generator and its filling-orifice, of the slotted or grooved hangers, the jar, with its trunnions, operating in such slots or grooves, and the valve operating automatically to open or close the mouth 95 of the jar with changes in position of the latter, substantially as described.

12. The combination, with the reversible jar and a hook upon the same, of the rock-shaft, with its hook, and the hand-latch controlling such rock-shaft, substantially as and for the purposes stated.

JAMES A. SHEPARD.
